(57) **CLAIM**

The ornamental design for a kitchen cutlery handle, as shown and described.

DESCRIPTION

FIG. 1 is a perspective view of a kitchen cutlery handle showing my new design.

FIG. 2 is a right side elevational view thereof.

FIG. 3 is a left side elevational view thereof.

FIG. 4 is an enlarged front elevational view thereof.

FIG. 5 is an enlarged rear elevational view thereof.

FIG. 6 is a top plan view thereof; and,

FIG. 7 is a bottom plan view thereof.

The broken lines for the cutlery blades and logo on the handle in FIGS. 1-7 represent environmental subject matter and form no part of the claimed design.

1 Claim, 4 Drawing Sheets
